UNITED STATES PATENT OFFICE.

LEWIS H. HAWES, OF BROOKLYN, NEW YORK.

BUCKLE.

SPECIFICATION forming part of Letters Patent No. 689,079, dated December 17, 1901.

Application filed August 18, 1900. Renewed September 4, 1901. Serial No. 74,327. (No model.)

To all whom it may concern:

Be it known that I, LEWIS H. HAWES, a citizen of the United States, residing in the borough of Brooklyn, in the county of Kings and city and State of New York, have invented certain new and useful Improvements in Buckles, of which the following is a specification.

This invention relates to tongueless buckles; and the object of the invention is to provide a buckle which shall be relatively flat and thin, of simple construction, and adapted to grip the strap or belt to be held firmly when a strain is applied to the strap.

15 In the accompanying drawings, which illustrate an embodiment of the invention, Figure 1 is a sectional view of the buckle and strap, the plane of the section being indicated by line α ' in Fig. 2. Fig. 2 is a plan of the buckle and strap. Fig. 3 is an elevation showing the end of the buckle. Fig. 4 shows the bail of the buckle detached. Fig. 5 is an edge view of the buckle detached. This view represents a larger buckle than those in the other 25 figures. Fig. 6 shows an embodiment of the invention wherein one of the side bars of the buckle-frame is omitted, and Fig. 7 is an embodiment where the channel is omitted from the bearing-bar of the frame.

30 The buckle consists of two loosely-connected parts—namely, the frame A, here shown as made of sheet metal, and the bail B, here shown as made of wire. The frame A is rectangular and comprises end bars 11, side bars 22^X, and a channeled bearing-bar 3 parallel with the side bars. At its respective ends the bar 3 has keepers or recesses 4, Fig. 2, to receive and retain the bail B. This bail is in the form of an oblong loop or ring and 35 40 has an attaching-bar 5 for the strap and a clamping-bar 6 to clamp on and hold fast the other end of the strap or another strap. This loop or bail B extends loosely about the frame A and loosely engages the keepers 4 in the 45 end bars of same.

C is the strap attached to the bail B, and C^X is the other strap secured by the buckle. These may be, of course, opposite ends of the same strap or belt. The strap C may be secured in any known way to the bar 5 of the bail, and this secures the buckle to this strap. When the strap C^X is to be secured by the

buckle, it is passed up through the frame (at a in Fig. 1) and then under the clamping-bar 6 of the bail B. A strain in opposite directions on the straps C and C^X will then cause the bar 6 to press the strap C^X down into the channel of the bar 3, as seen in Fig. 1, and hold it rigidly. Nevertheless, a pull on the end (at the left in Fig. 1) of the strap C^X will draw it through the bail and take up more of the strap. The free end of the strap C^X may, if desired, be tucked down under the other side bar 2^X of the frame, as seen in Figs. 1, 2, and 3; but this tucking is not at all essential to the buckling or clamping. The strap will be held securely without it.

In Fig. 5 the full lines show the bail B as hanging in the normal way in the channeled bar of the frame, and the dotted lines show it pressed upward or elevated, so that the end of the strap C^X may be threaded through it. Preferably the shoulder 7 of the recess 4, at the left in Fig. 5, will be turned up, as shown, so as to sustain the bail in a nearly erect position in order that the strap C^X may be the more readily passed through the bail under the bar 6.

This invention is not limited to any particular kind of material; but preferably the frame 80 will be made of sheet metal and the bail of wire. The bar 5 of the bail may have on it a sleeve of thin sheet metal or other sheet material. This has not been shown, as it is a common feature in buckles and is not deemed 85 essential.

It would be possible to dispense with the side bar 2^X. A construction where this bar is omitted is illustrated in Fig. 6. This view will need no special description.

The channel in the intermediate or bearing bar 3 is to insure the clamping fast of the strap and to allow the clamping-bar 6 to embed itself in the material; but if the bar 6 were angular, as seen in Fig. 7, it would clamp the strap 95 quite firmly on a plane-surfaced bearing-bar, as the bar 3^X in this figure.

Having thus described my invention, I claim--

1. In a buckle, the combination with a frame 100 having a side bar or keeper, a channeled bar, and recesses or niches at its respective ends, of a loose bail, embracing said frame and engaging the recesses therein, said bail having

a bar for attaching a strap, and a clamping-bar, substantially as set forth.

2. In a buckle, the combination with the frame having end bars, two side bars, a channeled intermediate bar, and niches or recesses in its end bars to receive the bail, of the said bail, of oblong, loop-like form, loosely embracing the frame at the channeled bar and engaging the recesses in the frame, said bail having an attaching-bar and a clamping-bar substantially parallel therewith, as set forth.

3. In a buckle, the combination with a substantially flat frame having end bars, a side

bar, a bearing-bar parallel with the side bar, and keepers or recesses at its ends, of the oblong bail loosely embracing the frame at the bearing-bar and engaging the keepers at the ends of same, substantially as set forth. 15

In witness whereof I have hereunto signed my name, this 16th day of August, 1900, in the presence of two subscribing witnesses. 2c

LEWIS H. HAWES.

Witnesses:

PETER A. ROSS,
HAROLD J. HIRST.
